Application October 21, 1947, Serial No. 781,060

6 Claims. (Cl. 226—75)

1

This invention relates to receptacle fillers and cappers. More particularly, this invention relates to manually operable receptacle fillers and cappers.

The objects of this invention include the provision of a manually operable receptacle filler and capper, provided with automatic indexers whereby to secure the proper alignment between the receptacles to be filled and the filling heads of the filler, as well as to secure the proper alignment between the receptacles to be capped and the capping head.

It is common practice in the conventional type of manually operable receptacle fillers and cappers of the type contemplated by this invention, for the operator to align the receptacles to be filled with the receptacle filling valves or to align the receptacle to be capped with the capping head immediately prior to the filling or capping operation. This is particularly true in such instances in which the device is provided with a single capping head, which may be moved from one receptacle to another during the completion of the capping operations.

The objects of this invention, therefore, include the provision of an improved, manually operable receptacle filler and capper; in which a set of a plurality of receptacles may be received and presented in successive order to a corresponding set of filling heads and at the same time to place the previously filled receptacles in capping position; in which the receptacle support is provided with bottle centering guides to properly center the bottles on the receptacle support in alignment with the filling heads and the zone of movement of the receptacle capper; in which all of the receptacles on the receptacle support table may be simultaneously manipulated, either rotatively or vertically, to be thus placed in proper position for filling or capping; in which indexing means are provided in association with the filling table on which the receptacles are properly centered and also in association with the capping head to properly align the receptacles with the filling heads and with the zone of movement of the receptacle capper; in which the receptacle support is provided with a plurality of sets of receptacle stations; in which the receptacle support is manually operable; in which the means for vertically actuating the receptacle support is manually operable; in which the receptacle support may be adjusted to compensate for the difference and height of different receptacles; and in which the means for vertically actuating the receptacle

2

support is automatically locked in either the uppermost or lowermost position of the receptacle support.

The foregoing and other objects and advantages of this invention will become more apparent and will be more readily understood when considered in connection with the drawings of the preferred embodiment of the present invention, which, without desire of limitation, will be described and illustrated as an improved type of apparatus for filling and capping milk bottles.

In the accompanying drawings:

Figure 1 is a perspective view of the improved receptacle filling and capping apparatus.

15 Figure 2 is plan view thereof.

Figure 3 is a side, elevational view thereof. Figure 4 is a front, elevational view thereof, from which the base has been omitted.

20 Figure 5 is a sectional view, taken along line 5—5 of Figure 4 of the drawings.

Figure 6 is a sectional view, taken along the line 6—6 of Figure 3 of the drawings.

25 Figure 7 is a view taken along line 7—7 of Figure 3 of the drawings.

Referring to the drawings, in which like numerals are used to identify like elements, the applicants' invention in an improved bottle receptacle filler and capper contemplates the use of a base 1, open at the top and bottom thereof.

30 Base 1 is provided toward the rear portion thereof with two upwardly extending tank supporting legs 2, which are securely fixed at their lower ends, as by welding, to the base 1, and securely fixed at their upper ends, as by welding, to the base plate 3 of the filler tank 4.

35 A bottle turn-table support leg 5 is pivoted in a suitable bearing in the front portion of the filler base 1. Although the vertical leg 5 is maintained in fixed vertical position, downward axial motion of the leg 5 is prevented by the collar 6, which is suitably keyed to the leg 5 and rests against a suitable upper bearing surface on the frame 1, thereby supporting the leg 5.

40 Upward motion of the leg 5 is prevented by 45 the collar 7 which is suitably keyed to that portion of the lower end of leg 5, which extends through the associated bearing in the support 1, against the end of which bearing the collar 7 is snugly fitted.

45 A horizontally extending bracket element 8 is suitably secured, as by welding, at one end to the filler base plate 3, and is provided at its opposite end with the collar portion 9, telescoped over the upper end of the cylindrical leg member 5. The inner surface of the collar 9 is in

bearing contact with the adjacent portion of the outer surface of the leg 5, thereby stabilizing the tank 4 and leg 5.

Collars 10 and 11, respectively, are keyed to the vertical leg 5, immediately above and below the collar 9 with the surface of the collars 10 and 11 which are adjacent to the surface of the collar 9 abutting thereagainst. Collars 10 and 11 prevent any relative vertical motion between the collar 9 and the leg 5. To prevent any undesirable relative, radial motion between the collar 9 and the leg 5, a locking screw 12 threaded through the collar 9, is adapted to engage the outer wall of the leg 5, so as to prevent such undesired relative rotation when the inner end of screw 12 is in engagement with shaft 5.

For the purposes of sanitation, the base 1 is provided with three feet 13, which are of a suitable length to support the base or frame 1 at a convenient distance from the floor of the dairy plant in which the applicants' improved bottle filler and capper may be used. Feet 13 permit ready cleaning of the floor beneath the bottle filler and capper, and the ready cleaning of the interior of the frame 1.

As clearly illustrated in Figure 3 of the drawings, the filler tank 4 is laterally disposed with respect to the front leg 5 of the filler. The bottle turntable or receptacle support assembly 14, the bottle capper 15 and turntable elevator 16 are rotatably supported on the front filler leg 5.

Turntable or receptacle support assembly 14, in its preferred embodiment, consists of a flat, rectangular receptacle supporting surface 17, which is provided with a centrally positioned aperture, through which the vertical leg 5 extends. The receptacle support surface 17 is securely fixed to and rests upon the receptacle support elevator 16. The receptacle support elevator 16 includes an internally threaded tube 18, telescoped over the cylindrical, vertical leg 5, and maintained in axial alignment therewith by the journals 19 and 20 at the upper and lower ends, respectively, of the tube 18. The vertical leg or shaft 5 is provided with a peripheral thread 21. Thread 21 has a larger root diameter than the outer diameter of the leg 5, and is complementary to and engages the threads 22 in the inner face of the tube 18.

A slideable hub 23, telescoped over tube 18, is provided on its inner periphery with a bearing 24, locked into position within the hub 23 by any suitable means, as, for example, by a tongue and groove arrangement. The inner cylindrical surface of the bearing 24 is in close bearing and sliding contact with the outer surface of the tube 18. The upper end of the hub 23 extends through the central opening in the receptacle turntable bottle support surface 17, with the outer face of the hub 23 snugly engaged in the central opening in the support 17. The turntable assembly 14 rests upon the annular flange 25, which extends outwardly from the upper portion of the outer periphery of the hub 23.

The lower portion of the hub 23 terminates in an outwardly extending, annular flange 26, which is provided on its lower face with a replaceable friction resisting disk or wear plate 27, which is secured to the flange 26 in any suitable manner.

Formed integrally with the hub 23 are the aligned, laterally projecting, indexing bars 28, which lie in a plane parallel to the axis of the shaft or support leg 5.

The tube 18 is supported in predetermined axial

position with respect to the shaft 5 by means of the interengagement of the screw threads 21 and 22. Although the shaft 5 is fixed in position, the relative, vertical position of the tube 18 on the shaft 5 may be varied by the relative rotation between the shaft 5 and the tube 18, which may be accomplished by the rotation of the shaft 5. A bracket element 29 is snugly telescoped over and permanently secured in any suitable manner to the lower end of the tube 18 and may be supported thereon by the flange of the lower bearing or journal 20.

The portion of the bracket 29, which extends inwardly toward the filler tank support legs 2, is provided with an aperture through which the guide shaft 30 extends. The guide shaft 30 is locked in place in the bracket 29 by any suitable means, such, for example, as a set screw. The lower end of the guide bar 30 extends into a close fitting socket in the frame 1, in which socket the guide shaft 30 is freely movable in a vertical manner. By this arrangement, the bracket 29 is prevented from rotating upon the support shaft or leg 5.

The wear plate 27 of the hub 23 rests upon the cams 31, which are carried by the rock shaft 32, suitably journaled in the ported lugs 33 formed integrally with the bracket 29. The rock shaft 32 may be actuated by means of the crank 34, formed on one end thereof. By the partial rotation of the crank 34, with the resulting partial rotation of the rock shaft 32, the cams 31 are rotated about the axis of the rock shaft 32, with the resultant raising or the gravity lowering of the hub 23, and the associated bottle support table 17.

As clearly indicated in the drawings, each of the cams 31 consist of a hub portion 35, secured to the shaft 32. The wing portions 36 of cams 31 extend in both directions tangentially from the outer periphery of the hub 35. In each instance the end of the wing 36 is provided with a rounded elbow portion 37, the extreme end 38 of which is nearer the axis of the rock shaft 32 than the angle portion 39. When the cams 31 are oscillated with the shaft 32 in a direction to force the cam elbow 37 against the plate 27, the hub 16 is elevated until the wing 36 of the cam 31 is in a substantially vertical position. In that position the friction plate 27 of the hub 16 rests on the slightly downwardly directed elbow end 37 of the cam 31 beyond the angle portion 39. The further rotation of the cam 31 in the mentioned direction is prevented by the abutment of the free end of the cam wing 36 against the adjacent face of the bracket 29, thereby locking the cam 31 and the rock shaft 32 in position, supporting the hub 16 in its uppermost vertical position. To lower the hub 16 and the associated bottle support table 17 to the lowermost position, it is necessary only to oscillate the rock shaft 32 in the opposite direction until the end 38 of the cam wing 36 beyond the elbow 37 engages the adjacent face of the bracket 29, in which latter position the friction face 27 of the hub 16 will rest upon the extended face of the cam wing 36.

When the hub 16 is in its lowermost position, it may be rotated through a maximum arc of approximately 180 degrees. The rotation of the hub 16 in one direction is limited by the engagement of one of the indexing bars 28 with the side of the guide shaft 30 positioned immediately to the rear of the hub 16. The rotation of the hub 16

in the opposite direction is limited by the engagement of the opposite guide bar 28 with the opposite side of the guide shaft 30.

To accurately position the turntable 17 in its elevated position, the guide shaft 30 is provided at its upper end with a cross bar 40, having at each end thereof a downwardly depending lug 41, spaced from the guide shaft 30 a distance approximately equal to the width of the indexing bars 28. When the hub 16 has been rotated in the desired manner, until a guide bar 28 abuts against the side of the guide shaft 30, the crank 34 may then be partially rotated so as to turn the cam 31 to elevate the turntable support hub 16. As the turntable support hub 16 is elevated, the indexing bar 28 is forced into position between the guide shaft 30 and the associated depending indexing lug 41, thereby locking the hub 16 and the associated receptacle support table 17 against relative, rotary motion on the shaft 5 when in their relative elevated positions.

In the event that undue wear on the indexing bar 28, the shaft 30, or the depending lugs 41 should result in improper indexing of the hub 16 and the associated turntable 17, the cross bar 40, which is keyed to the shaft 30, may be rotated slightly on the shaft 30, thereby decreasing the available spacing intermediate the shaft 30 and the depending lugs 41 for receiving the indexing bars 28.

The receptacle support or turntable 17 is provided with two receptacle guide arms 42 and 43, respectively, as clearly shown in Figure 7 of the drawings. Each of the guide arms 42 and 43 are provided at each end with laterally extending, bottle engaging prongs, sufficient to engage four receptacles. The prongs are so constructed that each set of prongs adapted to engage a receptacle will engage the receptacle on at least four points, thereby to accurately center either a rectangular-shaped receptacle or a circular receptacle in predetermined position on table 17. The guide bar 43 is provided at each end with laterally extending prongs 45, arranged in opposed order to the laterally extending prongs 44 on the corresponding ends of the guide bar 42. The ends of the guide bars 43 are superimposed on the ends of the guide bar 42, and each of the ends of the guide bars 42 and 43 are provided with aligned slots 46. One set of slots 46 registers on the guide stud 47 while the remaining set of slots 46 registers on the stud 48.

As mentioned, the ends of the guide bar 43 are superimposed on the ends of the guide bar 42 and the guide bar 43 rests upon the guide bar 42. The guide bar 42, in turn, rests upon the spacers 49, which are telescoped over the capped guide studs 47 and 48. The lower ends of the studs 47 and 48 pass through the receptacle support table 17 and are secured thereto in any suitable manner.

With respect to the guide stud 47, the lower end thereof is threaded, and it is secured to the table 17 by means of the thumb nut 50, which, when tightened, securely locks the ends of the guide bars 43 and 42 to the guide stud 47, to thereby maintain them in locked position. Upon the release of the thumb nut 50, the guide bars may be moved back and forth to the limit permitted by the inter-action of the slots 46 and the associated guide studs 47 and 48.

To assure the uniform, complementary movement of both of the guide bars 42 and 43, there is provided an equalizer bar 51, pivoted on the vertical shaft 5, immediately above the upper surface of the bottle support table 17. The ends of

the equalizer bar 51 are slotted to receive the dogs 52, which depend from the mid-portion of the bars 42 and 43.

As viewed in Figure 7 of the drawings, all of the bottle positioning prongs on the guide bar 42 are those prongs of each set of prongs furthest removed from the reader. All of the remaining prongs are on the guide bar 43. It, therefore, becomes obvious that by moving the guide bar 43 one way or the other, all of the bottle gripping prongs 45 forming a part of bar 43 will also be moved in the same direction. Equalizer bar 51, pivoted to the shaft 5 and linked to the guide bars 42 and 43 by the dogs 52, will cause the complementary movement in the opposite direction of the guide bar 42 and the associated prongs 44. In this manner, all of the bottle gripping prongs 44 and 45 will be moved either toward or away from the center of the position upon which a bottle is to be supported on the bottle support table 17. After a suitable adjustment in the guide bars 42 and 43 has been made, they may be locked into the adjusted position by the tightening of the thumb nut 50.

The capper assembly 15 is supported on the upper end of the capper and turntable support leg 5 by means of hub 53, which is swiveled to the upper end of the shaft 5, rests upon collar 10, and is provided adjacent the lower end thereof with two depending, rearwardly and outwardly extending indexing dogs 54, the lower ends of which straddle the bracket 8. The swinging or oscillatory movement of the capping head 15 about an axis coincident with the axis of the shaft 5, the axis of hub 16 and the axis of turntable receptacle support 17 is limited in either direction by the engagement of bracket 8 with one or the other of the indexing dogs 50.

The capper support arm 55 extends horizontally from the side of the hub 53, opposite the spacing dogs 54, and is provided at its outermost end with spaced arms 56, which are provided on their opposed inner faces with opposed vertical grooves 57 to receive opposed flanges on the capper element 58. Grooves 57 provide vertical guideways for the vertical reciprocation of the capper 58.

The capper 58 is supported by means of linkage 59 on a capper actuator or handle 60, which is pivoted for vertical oscillation to handle support brackets 61, formed along the upper edge of the capper support arm 55. A spring guide 62, which is pivoted to the handle 60, and which extends downwardly through an aperture in the capper support 55, is provided with a compression spring 63, which is telescoped over the spring guide 62. Spring 63 is compressed between a shoulder on the upper end of the spring guide 62, and the adjacent face of the capper support 55, thereby maintaining the handle 60 in its uppermost position. The lower end of the spring guide 62 is provided with a suitable lock means adapted to engage an adjacent surface of the capper support 55, when the handle 60 is raised by the spring 63 to thereby limit the maximum elevation of the handle 60.

The dimensions of the capper support arm 55, and the capper 58, are such that the bell 64 of the capper 58 is adapted to be moved, by the swinging of the handle 60, along an arcuate path which has the same radius as the arcuate path along which are positioned the filling heads 65 in the lower surface of the filler bowl 4. The bottle support positions on the filling table 17 intermediate the opposed bottle guide fingers 44

and 45 are also each spaced along an arcuate path similarly centered on the shaft 5. This latter arcuate path has the same radius as that of the arcuate path for the capper bell 64 and the filling heads 65.

It, therefore, follows that bottles, placed on the filling table 17 intermediate the bottle guide fingers 44 or 45, in any position of appropriate adjustment thereof, will always be centered along an arcuate path spaced from the center of the vertical turntable support axis 5, a distance equal to the spacing of the capper head bell 64 and the filling nozzle 65 from the same vertical axis.

By this design expedient, it is possible to place empty bottles to be filled upon the turntable support 17 at any angle of rotation thereof, move them into position below the filling heads 65, rotate the crank 34 until the mouth of the bottles are pressed against the associated filling heads 65, so as to enable the filling of liquid thereinto. Incidental to such elevation of table 17, the indexing bars 28 will be moved into position between the guide shaft 39 and guide dogs 41, thereby indexing the table 17.

Upon the completion of the filling of the receptacles under the filling head 65, the crank 34 is partially rotated in the opposite direction, sufficient to lower the turntable support 17 to its lowermost position. In the lowered position, the support 17 may then be rotated through an angle of 180 degrees, to move the filled receptacles into position below the path of motion of the capper bell 64. The crank 34 is then once again rotated in a direction to lift the turntable 17 to bring the mouth of the filled bottles into capping position and again to index the table 17. With table 17 again indexed, the bottles may then be capped in sequence by the actuating of the capper actuator 68 after first aligning the capper bell 64 with the bottle to be capped. The alignment of the capper bell 64 with the bottle to be capped is accomplished by the swinging of the capper support arm 55 into one or the other of its extreme limits of horizontal motion, which limits are determined by the engagement of one or the other of the dogs 54 with the bracket 8. When the capper has been moved into such extreme position, the bell 64 of the capper 58 will be in exact alignment with a receptacle held intermediate the bottle guide jaws 44 and 45 on the indexed turntable 17.

The present invention contemplates the provision of a bottle filler and capper adapted for use in the filling of receptacles of varying height, as well as varying diameter. The manner of accomplishing the necessary adjustment of the prongs 44 and 45, to permit the handling of receptacles of different diameters or different shape, has hereinbefore been described. To adjust the improved filler and capper for the handling of bottles of varying height requires the raising or lowering of the turntable assembly 14 and the associated elevator hub 16, and the guide shaft 30, all of which are supported by means of the internally threaded tube 18 upon the capper and turntable support 5.

As previously mentioned, collar 13 and the associated bracket 29, although supported directly upon the shaft 5 by means of the internally threaded tube 18 and the threaded portion of the shaft 5, are not rotatable thereon. Also, as previously mentioned, the shaft 5 is rotatable when not locked in position by the thumb screw 12 in the collar 9 of the bracket 8. Upon the release of the thumb screw 12, the shaft 5 may

be rotated in either direction, by appropriately turning the hand grip 66 at the top of the shaft 5, thereby either elevating or lowering the tube 18 upon the shaft 5 by means of the interaction of the screw and screw threads 21 and 22. By this procedure, the elevation of the turntable assembly or receptacle carrier 14 may be adjusted to any such elevation as may be required for filling and capping of bottles of different heights. When the desired elevation of the table 17 has been secured, the shaft 5 is again locked in position to prevent further rotation thereof by the re-tightening of the thumb screw 12 in the collar 9.

15 The present invention provides an improved, manually operable bottle filler and capper, which embodies all of the design objectives and advantages hereinbefore mentioned and which embodies the automatic indexing advantages, whereby to assure the proper alignment between the bottles to be filled and the filling heads, and the bottles to be capped and the capping heads, when the filling and capping table is elevated into operative filling and capping position.

20 Having thus described and illustrated the preferred embodiment of the present invention in an improved, manually operable bottle filler and capper, the invention is not to be restricted to the specific embodiment thereof, as illustrated in the drawings and as hereinbefore described, except insofar as may be necessary in view of the disclosure of the prior art and the appended claims.

25 The invention is hereby claimed as follows:

30 1. A receptacle filling and capping apparatus, comprising, in combination, a support, a rotative receptacle carrier, a filling head overhanging a receptacle supporting portion of said rotative receptacle carrier, a capper pivoted for oscillatory movement about an axis coincident with the extension of the axis of said rotative receptacle carrier and movable through an arc overlying a receptacle support portion of said receptacle carrier, depending index means on and rotatable with said carrier, a stop on said support interposed in the path of rotation of said index means to arrest the rotation of said carrier at a selected position, and means for arresting the oscillatory movement of said capper at a selected position over said carrier comprising a depending projection on said capper adapted to oscillate therewith and an extension on said support in the path of oscillation of said projection and engageable thereby.

35 2. A receptacle filling and capping apparatus comprising in combination a support, a receptacle platform rotatably mounted on said support, a carrier disposed over said receptacle platform swiveled to said support for pivotal oscillatory movement about an extension of the rotative axis of said receptacle platform, a capper bracket disposed over said receptacle platform swiveled to said support for oscillatory movement about an extension of the rotative axis of said receptacle platform, a depending projection on said capper bracket and a co-operating indexing extension on said support engageable thereby for arresting movement of said capper bracket at a selected location over said receptacle platform, a capper supported on said bracket and swingable therewith along a restricted arcuate path over a portion of said receptacle platform, receptacle filling means disposed over said receptacle platform at a position beyond the restricted arcuate path of said capper bracket and at substantially the

same radial distance from said rotative axis as said capper, an outwardly extending indexing member spaced axially from and adapted to rotate with said receptacle platform, and a projection on said support interposed in the rotative path of said indexing member and adapted to be engaged thereby upon rotation of said receptacle platform to arrest rotation thereof at a selected position to align a selected portion of said platform with said receptacle filling means and to align another selected portion of said platform with said capper when the capper carrier is moved to one end of its restricted arcuate path.

3. In a receptacle filling and capping apparatus the combination of a support, a receptacle platform adapted to be elevationally adjusted and intermittently rotated on said support, a capper carrier superposed above said receptacle platform and pivoted to said support for oscillatory movement about an extension of the rotative axis of said receptacle platform, a capper bracket disposed over said receptacle platform swiveled to said support for oscillatory movement about an extension of the rotative axis of said receptacle platform, a depending projection on said capper bracket and a co-operating indexing extension on said support engageable thereby for arresting movement of said capper bracket at a selected location over said receptacle platform, a capper actuator supported on said capper bracket and hinged thereto, a capper associated with said capper bracket and capper actuator adapted to be swung therewith along a restricted arcuate path over said receptacle platform, a receptacle filling head superposed over said receptacle platform beyond the restricted arcuate path of said capper, an outwardly extending indexing member spaced axially from and adapted to rotate with said receptacle platform, and a projection on said support extending into the rotative path of said indexing member and adapted to arrest rotation of said receptacle platform at a predetermined position so as to align a selected portion thereof under said capper when the latter is positioned at an end of its restricted arcuate path and so as to align another selected portion thereof under said receptacle filling head.

4. In a receptacle filling and capping apparatus the combination of a support, a platform adapted to be intermittently rotated on said support, a plurality of receptacle holders on said platform, a capper carrier superposed above said receptacle holders and pivoted to said support for oscillatory movement about an extension of the rotative axis of said platform, a capper bracket disposed over said receptacle platform swiveled to said support for oscillatory movement about an extension of the rotative axis of said receptacle platform, a depending projection on said capper bracket and a co-operating indexing extension on said support engageable thereby for arresting movement of said capper bracket at a selected location over said receptacle platform, a capper actuator supported on said capper bracket and hinged thereto, a capper associated with said capper bracket and capper actuator adapted to be swung therewith along a restricted arcuate path over said receptacle holders, and a receptacle filling head superposed over said receptacle holders substantially diametrically opposite the restricted arcuate path of said capper, said platform having an outwardly extending indexing member spaced axially from and adapted to rotate with said platform, and said support having a projection extending into the rotative

path of said indexing member and adapted to arrest rotation of said platform at a predetermined position so as to align a selected receptacle holder with said capper when the latter is positioned at an end of its restricted arcuate path and to align another selected receptacle holder with said receptacle filling head.

5. In a receptacle filling and capping apparatus the combination of a support, a platform adapted to be intermittently rotated on said support, a plurality of receptacle holders on said platform, a capper carrier superposed above said receptacle holders and pivoted to said support for oscillatory movement about an extension of the rotative axis of said platform, a capper bracket disposed over said receptacle platform swiveled to said support for oscillatory movement about an extension of the rotative axis of said receptacle platform, a depending projection on 10 said capper bracket and a co-operating indexing extension on said support engageable thereby for arresting movement of said capper bracket at a selected location over said receptacle platform, a capper actuator supported on said capper bracket and hinged thereto, a capper associated 15 with said capper bracket and capper actuator adapted to be swung therewith along a restricted arcuate path over said receptacle holders, and a receptacle filling head superposed over said 20 receptacle holders substantially diametrically opposite the restricted arcuate path of said capper, said platform having an outwardly extending indexing member spaced axially from and adapted to rotate with said platform, and said support 25 having a projection extending into the rotative path of said indexing member and adapted to arrest rotation of said platform at a predetermined position so as to align a selected receptacle 30 holder with said capper when the latter is positioned at an end of its restricted arcuate path 35 and to align another selected receptacle holder with said receptacle filling head, each of said receptacle holders comprising a pair of cooperating receptacle engaging jaws, each of said jaws 40 being attached to a corresponding bracket on said platform, and each of said brackets being mutually adjustable with respect to the other to provide a space between the respective cooperating jaws to receive a receptacle of a predetermined size and shape.

6. In a receptacle filler and capper the combination of a capper swiveled to a capper supporting post, a capper supporting bracket, said capper being adapted to be oscillated in a horizontal plane about the axis of said post for capping operations in an arc of a circle concentric to the axis of said post, a filler tank, filling heads associated with said tank and positioned in another arc of said circle concentric to the axis 55 of said post, a receptacle carrier rotatably mounted on said post at a level below that of said capper and said filling heads whereby a receptacle on said carrier may be moved in a circular path 60 under said circle concentric to the axis of said post, 65 means for vertically actuating the receptacle carrier for movement of a receptacle thereon into receptacle filling engagement with a filling head and for movement of a receptacle thereon into receptacle capping position, a depending 70 projection on said capper bracket and a co-operating indexing extension on said support engageable thereby for arresting movement of said capper bracket at a selected location over said receptacle carrier, an outwardly extending indexing member spaced axially from said carrier 75

2,650,012

11

and adapted to rotate therewith, and a projection on said post extending into the rotative path of said indexing member and adapted to be engaged by said indexing member at either side of said projection so as to arrest rotation of said carrier at either of two predetermined positions, in one of which said positions a receptacle on said carrier is aligned with a filling head and in the other of which said positions such receptacle is aligned with the capper when said capper is positioned at an end of its arc of oscillation.

THEODORE H. KUMMER.
RAYMOND E. BODENDOERFER.
